United States Patent Office

Des. 175,468
Patented Aug. 30, 1955

175,468

HURDLE

David L. Holmes, Detroit, Mich.

Application October 22, 1954, Serial No. 32,789

Term of patent 14 years

(Cl. D34—5)

The single figure is a perspective view of a hurdle, showing my new design.

I claim:

The ornamental design for a hurdle, as shown.

References Cited in the file of this patent

UNITED STATES PATENTS

1,910,080 Austin May 23, 1933

2,119,808 Fecht June 7, 1938
2,583,786 Marzucco Jan. 29, 1952
2,706,631 Holmes Apr. 19, 1955

FOREIGN PATENTS

Germany May 20, 1922
Sweden Nov. 16, 1937
Australia July 9, 1951